COUPLING SYSTEM FOR MULTIPLE WAVE BAND CIRCUITS

John D. Reid, Philadelphia, Pa., and Loren R. Kirkwood, Collingswood, N. J., assignors to Radio Corporation of America, a corporation of Delaware

Application April 27, 1937, Serial No. 139,122

6 Claims. (Cl. 250—20)

The present invention relates to multiple wave band receivers, and more particularly to high frequency interstage coupling systems therefor. It has for its primary object to provide an improved interstage coupling system for the high frequency amplifier circuits of a multiple wave band receiver.

It is a further object of the present invention to provide simplified compound coupling means 10 in a system of the above character, wherein two primary windings, resonant at different frequencies, are rendered effective as compound coupling means in conjunction with one or more tuned secondary windings.

15 It is also a further object of the invention to provide a compound coupling system for the higher frequency tuning bands of a multiple wave band receiver, wherein a low distributed capacity provided by one primary winding may be utilized to tune a second primary winding, whereby said second primary winding may function in two differing wave bands to provide improved energy transfer at the high frequency end of each wave band.

25 It is also an object of the present invention to provide a high frequency interstage coupling means for wave band change apparatus and the like, wherein two primary windings are included in series in the output circuit of an amplifier tube and are coupled to two differing secondary windings, and wherein the series connection provides a low distributed capacity of one primary winding in connection with the second primary winding, without requiring the high frequency circuit connections to be broken therebetween in wave band changing.

It is also a still further object of the present invention to provide a switching arrangement for the high frequency tuning bands of a multiple 40 wave band receiver, wherein the secondary windings of adjacent tuning bands are operated in parallel in the highest frequency band, thereby minimizing switching connections.

It is also an object of the invention to simplify 45 the switching arrangement and to provide a more effective energy transfer between primary and secondary circuits for the ultra high frequency tuning ranges of a multiple wave band receiver.

A multiple wave band tuning system to which 50 the coupling system of the present invention particularly relates is shown, described and claimed in an application of John D. Reid, Serial No. 118,631, for "Multiple wave band receivers", filed December 31, 1936. The present application relates particularly to the specific circuits and

means employed in the C and D bands for resonating the compound primary windings, and the use of the shunt connected compound secondary windings as referred to in that application.

The invention will, however, be better understood from the following description, when considered in connection with the accompanying drawings, and its scope will be pointed out in the appended claims.

In the drawings, Figure 1 is a schematic circuit 10 diagram of a radio frequency amplifier switching system embodying the invention, and

Figures 2 and 3 are similar schematic circuit diagrams showing the connections provided by the switching system of Fig. 1 in two high frequency tuning bands.

Referring to Fig. 1, the circuit includes coils 5, 6, 7, 8, 9 and 10 forming an inductance unit for tuning through four differing wave bands by means of a common variable tuning capacitor 20 section 11, in connection with the first detector 12 of a superheterodyne receiver which is arranged to receive amplified high frequency signals from a radio frequency amplifier tube indicated at 13.

The coil system provides a band tunable or 25 multiple wave coupling means between the radio frequency amplifier tube 13 and the first detector 12, and may be considered as the radio frequency tuning means of the receiver. A separate coil unit comprising a primary winding 14 and a secondary winding 15 is provided for the fifth and 30 highest frequency tuning range.

The tuning ranges referred to may include such bands as the "X", "A", "B", "C" and "D" bands, covering a frequency range in each band as indicated below:

	Kilocycles
"X" band	150—410
"A" band	530—1800
"B" band	1800—6500
"C" band	6500—22000
"D" band	22000—60000

It will be seen that the two higher frequency bands cover a tuning range between 6500 kc. and 45 60,000 kc. This high frequency range makes it necessary to use a minimum length of circuit leads and switching connections, for stable operation. In accordance with the invention, the connections are such that the winding 10 is included permanently in the anode circuit 16 of the amplifier 13 adjacent to the anode thereof and is connected in series with the highest frequency band primary winding 14 through a lead 17. The anode circuit, including the series windings, 50 55

receives anode potential through a lead 18, the highest inductance winding 5, and a connecting lead 19.

The coils 6 to 9, inclusive, are arranged to form, 5 each in turn, the main secondary windings for the "X", "A", "B" and "C" bands, as indicated by the letters adjacent to the coil sections, and are connected in series, with the winding 9 connected at its high potential end 20 to the grid circuit 21 of the detector 12 and to the stator of the tuning 10 capacitor 11. Coupling with the grid is provided by a coupling capacitor 22 and a grid resistor 23. By this arrangement the tuning capacitor is connected permanently to the high potential 15 terminal of the coil 9 which is the "C" band secondary, and to the grid circuit of the detector without switching connections.

The end terminals of the series connected coils 20 or windings and the junctions between the coils 20 are connected to a band change switch section at spaced fixed contacts 25 to 29, inclusive, as indicated. Further spaced fixed contacts are provided on the switch as indicated at 30, 31 and 32. A grounded capacitor 33 is connected with the 25 switch contact 30 and a series of grounded trimmer capacitors 34, 35, 36 and 37 are connected with the switch contacts 32. The contacts 31 in the switch are not connected in circuit. The low potential terminal 38 of the coil 6 and the contact 30 30 25 are coupled to the high potential end of the coil 5 and the lead 19 through a coupling capacitor 39.

The switch is preferably of the rotary type, 35 and is provided, in addition to the fixed contacts referred to, with three fixed contact strips or elongated contact elements 40, 41 and 42, which are located in spaced relation to the fixed contacts to provide the arrangement schematically illustrated, whereby certain bridging connections 40 may be made between the fixed contacts by three movable contact elements in a series of steps. The first is a bridging contact 43 which is movable along the grounded contact 41, to provide a bridging ground connection with the fixed contacts 25 45 to 28, progressively to the "C" band position shown, wherein the low frequency end of the "C" band coil or secondary 9 and the adjacent terminal end of the "B" band coil 8 are connected to ground. In the next position, for the "D" band, bridging connection is made between the contact 50 40 and the contact 29 to connect the "D" band secondary 15 in parallel with the secondary 9.

The second movable bridging contact element is indicated at 45 and, in the "C" band position shown, provides a bridging connection between the terminal 29 and one of the terminals 32, for connecting the trimmer capacitor 34 in parallel with the secondary coil 9 to adjust the tuning at the high frequency end of the "C" band.

The third movable connection comprises a 60 bridging element 47, for short circuiting the coils 6 and 7, whereby they are ineffective to absorb energy or to resonate in the "C" band tuning range, and for bridging the terminals 30 and 42, 65 whereby the capacitor 33 is connected substantially in shunt with the coil 8 to provide proper response in the "C" band as the low frequency primary of a compound coupling for the plate circuit 16 of the radio frequency amplifier 13 and the "C" band secondary coil 9, as will hereinafter be described. The contact 42 is also connected to the 70 anode circuit between the coils 10 and 14 with the lead 17, through a bypass capacitor 48 and a lead 49, whereby the series anode circuit connection, including the primary 14 for the "D" band,

is bypassed to place the winding 8 or "B" band secondary in series with the winding 10. The latter is in inductive coupling relation to the secondary 9 and provides a high frequency primary in conjunction with the winding 8 as the low frequency primary for the "C" band tuning range. 5

The switch connections established for the "C" band tuning are indicated more clearly in Fig. 2 in which the same reference characters are applied to like parts, as in Fig. 1. 10

Referring to Fig. 2, along with Fig. 1, the "C" band primary circuit outlined is also connected with a shunt path through the coil 14, the lead 19 and the capacitor 39. This path has a relatively high impedance, as the "X" band primary 15 coil 5 is of relatively high inductance and is in series with the primary coil 14 which also has an appreciable inductance effective in the "C" band range. In the main primary circuit, the bypass capacitor 48 is of relatively high capacity and 20 low reactance; for example, it may have a capacity value of .01 microfarad. Therefore, the desired primary circuit is obtained for the windings 10 and 8 without additional switching contacts to make and break additional circuits. 25

The plate capacity of the R. F. amplifier tube 13 and other stray distributed anode circuit capacity is indicated at 51. The trimmer capacitor 33 is connected in shunt with the coil 8 as the low frequency primary and is preferably tuned to 30 substantially 4800 kc. for the "C" band covering a range of 6500 to 22,000 kc., as indicated. The low frequency primary is therefore resonated below the tuning range of the secondary 9.

The distributed capacity 51 is in series with the 35 capacity value provided by the capacitor 33, and since the latter is relatively high with respect to the plate capacity 51, the plate capacity 51 is effectively connected in shunt relation to the high frequency primary winding 10 and serves to tune 40 it, in the present example, to substantially 40,000 kcs., which is above the "C" band tuning range. 45

The use of a compound coupling of this type is effective to increase the gain through the coupling circuit at both ends of the tuning range, 45 since the high frequency and the low frequency response of the primary windings 8 and 10 is effective to raise the overall response of the coupling system ends of the tuning range.

It has been found that at least one of the primary windings may be maintained in circuit and utilized in at least two higher frequency tuning bands without switching. It has been found also that that high frequency primary winding 10 is best adapted for this use, and therefore is maintained in circuit adjacent to the anode for both the "C" and "D" bands. The "D" band is higher in frequency, and in order to resonate the high frequency primary 10 above the "D" band, a differing capacity is provided in series with it and 60 is provided by a suitable low frequency primary such as the primary winding 14 which is caused to be effective for the "D" band, in the series anode circuit, by a simple switching operation involving only opening the connection through the 65 bypass capacitor 48 and short circuiting the low frequency primary for the "C" band, coil 8 to provide the circuit shown in Fig. 3, to which reference may be made along with Figs. 1 and 2. Except for the circuit connection change for the 70 "D" band, tuning the circuit is the same as shown in Fig. 3 and the same reference numerals are applied.

The low frequency primary coil 14 for the "D" band is provided with a relatively low distributed 75

capacity and is tunable thereby to substantially 1900 kcs. or below the "D" band, and the low distributed capacity then becomes the controlling capacity in tuning the high frequency primary 10, since the low distributed capacity of the coil 14 is lower than the tube capacity 51 with which it is effectively in series. The high frequency primary 10 operates in both the "C" and the "D" bands, resonating at a frequency above the "C" band in series with the primary 8 and its shunt capacity 33, and as shown in Fig. 3 it resonates at a still higher frequency above the "D" band when placed in series with the low distributed capacity of the primary coil 14. In the present example the distributed capacity of the coil 14 is sufficient to tune the coil 10 to substantially 90,000 kcs. or well above the "D" band which covers the range of 22,000 to 60,000 kcs.

In the circuit of Fig. 3, the winding 5 is effective 20 as a choke coil, as in the "C" band. However, the bypass capacitor 39, while offering appreciable impedance at 4800 kcs., is of relatively low impedance at 19,000 kcs. and serves as part of the low impedance path to ground from the lead 19, 25 as indicated.

By comparing the circuits in Fig. 1 and Fig. 3, it will be seen that the two secondary windings 15 and 9 are connected in parallel when the conductor 43 reaches the contacts 29 and 40. The 30 conductor 47 grounds the contact 28 and also the contacts 25, 26 and 27.

Since the coil 9 is of relatively high inductance with respect to the coil 15, parallel operation in the "D" band has been found to be permissible and 35 at the same time permits compound coupling whereby energy is supplied from the primary winding 10 to the coil 9 and from the coil 14 to the coil 15 for the "D" band operation. By this arrangement the tuning capacitor 11 and the tube 40 input circuit 21 may be maintained permanently connected with the major portion of the tuning inductance unit and likewise necessity for switching the high frequency primary 10 is eliminated. This winding is closely associated with the winding 9 and remains in circuit throughout the 45 switching operations for the various bands, thus preventing change in distributed capacity at the sensitive high frequency end of the tuned circuit.

While the coupling system of the present invention has been shown and described in its application to a radio frequency amplifier stage in the "C" and "D" band ranges, it may be provided in other multiple wave band apparatus between ultra high frequency circuits in a similar manner 50 and in other high frequency and ultra high frequency tuning ranges.

We claim as our invention:

1. In a tunable high frequency multiple wave band amplifier, the combination of means providing compound inductive interstage coupling between certain of the signal conveying circuits thereof and including a coupling winding having low distributed capacity and resonant at a frequency below a predetermined tuning band, a second coupling winding, and means for connecting said windings effectively in series whereby the distributed capacity of the first winding is effective to tune the second coupling winding to a frequency above said tuning band.

2. In a high frequency multiple wave band amplifier, the combination of two signal circuits, means providing compound inductive coupling between said circuits including two coupling windings connected in series in one circuit and resonant at different frequencies, a third coupling

winding having a low distributed capacity, and means for selectively connecting said third winding in series with one of said first-named windings to the exclusion of the other whereby said distributed capacity is effective to resonate said one winding to a higher frequency.

3. In a high frequency interstage coupling system for multiple wave band amplifiers and the like, the combination of two primary windings, resonant at different frequencies above and below a predetermined wave band, a secondary winding tunable through said wave band and coupled to receive signal energy from said high and low frequency primary windings jointly, and means for resonating the high frequency primary winding at a frequency above a predetermined higher frequency tuning band comprising a second low frequency primary winding, said second low frequency primary winding having a low distributed capacity effective to resonate said high frequency primary winding above said higher frequency tuning band.

4. In a high frequency interstage coupling system for multiple wave band amplifiers and the like, the combination of two primary windings, resonant at different frequencies above and below a predetermined wave band, a secondary winding tunable through said wave band and coupled to receive signal energy from said high and low frequency primary windings jointly, and means for resonating the high frequency primary winding at a frequency above a predetermined higher frequency band comprising a second low frequency primary winding resonant below said higher frequency band and connected in series with said high frequency primary winding, said second low frequency primary winding having a low distributed capacity effective to resonate said high frequency primary winding above said higher frequency band, a higher frequency secondary winding tunable through said higher frequency band coupled with said second low frequency primary to receive signal energy therefrom, and switching means for rendering the first low frequency primary ineffective as a coupling means 45 and for connecting said secondary windings in parallel.

5. In a multiple wave band receiver, the combination with a radio frequency amplifier, of an interstage tunable coupling means therefor comprising an output anode circuit for said amplifier, a primary winding permanently connected in circuit therewith at the high potential end of the anode circuit to provide a high frequency primary winding for said interstage coupling means, a pair of low frequency primary windings, and means for selectively connecting said last-named windings serially in circuit with the first-named winding and the anode capacity of said tube, the distributed capacity of one of said second-named primary windings being of a value lower than the anode capacity and effective to tune the high frequency primary winding to a predetermined high frequency when connected in circuit therewith.

6. In a multiple wave band receiver, a combination with the radio frequency amplifier, of an interstage tunable coupling means therefor comprising an output anode circuit for said amplifier, a primary winding permanently connected in circuit therewith at the high potential end of the anode circuit to provide a high frequency primary winding for said interstage coupling means, a pair of low frequency primary windings, and means for selectively connecting said last-

5 named windings serially in circuit with the first-named winding and the anode capacity of said tube, the distributed capacity of one of said second-named primary windings being of a value lower than said anode capacity and effective to tune the high frequency primary winding to a predetermined high frequency when connected in circuit therewith, a pair of secondary windings one coupled with each of said low frequency and

high frequency primary windings, a second tube having a grid circuit, a variable tuning capacitor, circuit means permanently connecting said capacitor and grid circuit with one of said secondary windings, and means for connecting said secondary windings in parallel conjointly operable with said first-named selecting means.

JOHN D. REID.

LOREN R. KIRKWOOD.
